UNITED STATES PATENT OFFICE.

CHARLES NORTH, OF NEWPORT, KENTUCKY, AND CHARLES J. MINNING AND THOMAS McWEENY, OF CINCINNATI, OHIO.

COMB.

1,159,789.

Specification of Letters Patent.

Patented Nov. 9, 1915.

Application filed October 22, 1914. Serial No. 863,015.

To all whom it may concern:

Be it known that we, CHARLES NORTH, CHARLES J. MINNING, and THOMAS McWEENY, citizens of the United States, and the said CHARLES NORTH being a resident of Newport, in the county of Campbell and State of Kentucky, and CHARLES J. MINNING and THOMAS McWEENY being both residents of Cincinnati, county of Hamilton, and State of Ohio, have invented a new and useful Improvement in Combs, of which the following is a full, clear, and exact description, reference being had to the accompanying drawings, forming a part of this specification.

Our invention relates to combs, and particularly to that class of combs used by ladies in dressing their hair for decorating the coiffure and retaining the arrangement of the same. Many, if not all, ladies desire, in connection with the proper arrangement of the coiffure, some perfume or extract for imparting to the hair a sweet and pleasant odor, and it is the object of our invention to provide, in a comb of the class mentioned, suitable means for retaining such perfume, whether in the form of a liquid extract or a powder, so that the same may be liberated in close proximity to the hair, thereby giving and imparting to the same a delicate and fragrant odor. In connection with such a device, it is a further object of our invention to provide means, in a comb constructed in accordance with the above requirements, for retaining the perfume against exhalation until required, so that the perfume placed in the comb at the time of arranging the coiffure need not be disseminated into the atmosphere until such time as its fragrance is especially required.

With such and other objects in view, as will more fully appear from the following description thereof, our invention consists in detail of the following construction.

In the drawings: Figure 1 is a back view of a comb constructed in accordance with our invention; Fig. 2 is a vertical section of Fig. 1; Fig. 3 is an enlarged view of the perfume receptacle; Fig. 4 is a section of the perfume barrel and receptacle; Fig. 5 is a detail of one means of placing the perfume in the receptacle; Fig. 6 is a detail of another means for placing a perfume in the receptacle.

The numeral 1 indicates a lady's comb of the kind used in retaining the permanent arrangement of the coiffure. Said comb may be made of any suitable material and may be of any design and provided with any desired ornamentation, as brilliants, gold and silver filigree work or otherwise. The back and teeth of said comb are indicated respectively by the numerals 2 and 3. Upon the back of said comb is placed a barrel 4 for the receipt of the perfume receptacle 5. The barrel 4 may be of any suitable size and shape consistent with the design of the comb and the ornamentation thereof, and may itself be comprised in the ornamental design of the back of said comb. The said barrel is provided with two rows of perforations 6, through which the perfume may be liberated or exhaled. The perfume receptacle 5 is designed to fit snugly inside the barrel 4 and to rotate therein. The said receptacle is provided with ornamental ends 7, which may be of any suitable design, and two longitudinal slots 8, which are so spaced on the receptacle that they may be made to register with the rows of perforations 6 in the barrel. One of the ends 7 is adapted to serve as a stopper for the receptacle 5. Near one end of the receptacle 5 a stud 9 is provided, said stud being adapted to enter into slight depressions 10 on the inside the barrel to retain the receptacle in either closed or open position, *i. e.* in the positions where the slots 8 are closed by the walls of the barrel and where said slots register with the perforations in said barrel respectively. The stud 9, it will be understood is permitted to pass from one to the other of said depressions during the rotation of the receptacle by reason of the slightly springy nature of the barrel construction. The stud and depressions as above described are, however, but illustrative of one construction by which the proper limitation of the rotation of the receptacle may be attained, and we contemplate as within the spirit of our invention such other suitable constructions as may be substituted therefor the nature of which will be obvious to those skilled in the art.

For the purpose of placing the perfume in the receptacle, we provide, where the perfume is in the shape of a liquid, an absorbent pad or sponge 11 which is adapted to fit inside the receptacle when saturated.

2
If a powder, or non-liquid perfume is used, a sachet bag 12 adapted to fit into the receptacle, as shown in Fig. 6 is provided.

The nature and use of our invention will 5 be apparent to those skilled in the art.

The sponge or bag having been provided with a suitable perfume and placed in the receptacle, said receptacle is placed in the barrel. If it is desired at once to use the 10 perfume, the receptacle is so placed in the barrel that the slots will register with the perforations, and the perfume will thus be liberated, the receptacle being held in this position by the stud resting in one of the 15 depressions inside the barrel. If the perfume is not immediately desired the receptacle is rotated so that the slots are closed by the barrel walls, where it is held by means of the stud 9 and one of the depressions 10. 20 When the perfume is later desired, it is merely necessary to give the receptacle a slight turn so that the slots register with the perforations.

Having thus described our invention, what we claim as new and desire to secure by Letters Patent, is:

In combination with an ornamental comb for the permanent arrangement of the coiffure, a barrel on said comb, a receptacle in said barrel, said receptacle being adapted to 30 rotate therein, perforations in said barrel, a slot in said receptacle adapted to register with said perforations, and a pad adapted to be saturated with perfume in said receptacle.

In witness whereof we have hereunto set our hands in the presence of two witnesses, at Cincinnati, Hamilton county, Ohio, this 15 day of October, 1914.

CHARLES NORTH.
CHARLES J. MINNING.
THOMAS McWEENY.
